CENTRIFUGAL TYPE SPEED GOVERNING
MECHANISMHarold M. Otto, Schenectady, N. Y., assignor to
General Electric Company, a corporation of
New York

Application February 19, 1942, Serial No. 431,604

7 Claims. (Cl. 264—17)

The present invention relates to centrifugal type speed governing mechanisms for controlling or actuating a machine element in response to speed changes or upon the occurrence of certain speed conditions. The invention is of particular significance in connection with centrifugal type emergency governing mechanisms although it is not necessarily limited thereto. Such mechanisms are used, for example, for shutting down prime movers such as elastic fluid turbines as their speed rises a certain percentage above the normal operating speed. In elastic fluid turbine arrangements it is in general customary to provide an emergency speed governor for closing the turbine stop and control valves when the speed rises about 10% above normal speed. Emergency governors in such arrangements constitute the final safety device of the turbine and for this reason should be in perfect operating condition. As it rarely occurs that an emergency governor has to operate to effect shutdown of a turbine, it is customary to test the governor at frequent intervals, particularly during starting and shutdown of the turbine, to assure that it is in safe operating condition. It is not desirable to carry out the testing or checking of the governor at the actual emergency speed for which the governor is designed and for this reason arrangements have been devised whereby the governor may be tested at a speed below the emergency speed. One such arrangement is disclosed in the patent to W. P. Dryer, No. 1,666,490, issued April 17, 1928, and assigned to the same assignee as the present application. According to these arrangements the mass of the flyweight is increased by the supply of liquid such as oil to a chamber formed by the flyweight. Thus a governing mechanism designed normally to act on an element at a speed of 2000 R. P. M. may be caused to actuate such element at a lower speed, say 1000 R. P. M., by the supply of oil to a chamber formed in its flyweight. Difficulties are experienced in case of governing mechanisms designed to operate at higher speeds of the order of 5000 R. P. M. and more when it is desired to test such mechanisms at much lower speeds of the order of 1000 R. P. M. The methods and arrangements heretofore used would necessitate the provision of flyweights forming very large chambers to permit the supply of an amount of liquid sufficient to cause actuation of the mechanism at much lower speed.

One object of my invention is to provide an improved construction and arrangement of governing mechanisms which may be used as emer-

gency governors and readily tested at a comparatively small fraction of their normal operating speed by a relatively small change of the mass of one of their flyweights.

Another object of my invention is to provide a governing mechanism with an improved and readily variable governor characteristic.

These and other objects are accomplished in accordance with my invention by the provision of a governing mechanism which includes at least two flyweights arranged to produce centrifugal forces opposing each other and producing together a differential or resultant actuating force for controlling or actuating a machine element. Each of the flyweights is biased by a separate spring against its centrifugal force. By properly choosing the spring characteristics, the masses of the flyweights and their normal radii of rotation, a governing mechanism may be produced in which the ratio of the centrifugal forces of the two flyweights varies in a desired manner with variations in speed.

For a better understanding of what I believe to be novel and my invention, attention is directed to the following description and the claims appended thereto in connection with the accompanying drawing.

In the drawing Fig. 1 illustrates a governing mechanism embodying my invention; and Fig. 2 is a section along line 2—2 of Fig. 1.

The arrangement illustrated in the drawing comprises a shaft 10 which may form part of an elastic fluid turbine and an emergency governing mechanism or unit 11 secured to the end of the shaft 10. The mechanism is arranged in co-operative relation with an element, in the present instance a trip finger 12, to cause shutting of turbine valves, not shown, as the turbine speed rises a certain percentage above the normal operating speed. The governor unit includes a support or cylinder 13 which has one end rigidly fastened to the shaft 10 and another end to which a cover 14 with a central opening 15 is secured. The cylindrical support 13 broadly constitutes a hollow extension of the shaft 10. Diametrically opposite portions of the cylindrical support 13 have openings 16, 17 forming seats for plugs or bushings 18 and 19 respectively. A governor spindle 20 projects through the plugs 18, 19 and has end portions located outside the support and connected to an emergency ring or main flyweight 21. The spindle 20 has sliding fit in the bushing 18 and is rigidly secured to the bushing 19, which latter has sliding fit in the support 13. The main flyweight 21 comprises axially spaced rings 22

and 23. The lower halves of the rings are united by an outer wall 24 which has end portions 25 turned inward and suitably secured to the adjacent surfaces of the rings 22, 23. The central portion of the outer wall 24 forms a boss 26 which has screw-thread connection with the lower threaded end of the spindle 20. The outer wall 24 and the side walls form two cups or chambers 27, 28 with discharge openings 29 and 30 respectively. During rotation liquid may be conducted into the chambers 27, 28 by a valved liquid supply conduit 31 through axial openings 32 with radial discharge ports 33 in the cylindrical support 13.

Upper portions of the axially spaced rings 22, 23 are united by a spacer or plug 34 with a central bore 35. The upper end of the spindle 20 projects into the bore 35 and has a slot 36 loosely connected to the plug 34 by a cotter pin 37. The main flyweight is biased towards the support against the action of centrifugal force by a spring 38 surrounding the lower portion of the spindle 20 with its lower end bearing against the plug 34 and its upper end bearing against a shoulder 39 on the spindle. This shoulder 39 is formed by a ring or nut 40 held on a threaded portion 41 of the spindle and locked thereto by a cotter pin 42. The threaded portion 41 of the spindle has a diametrical slot 43 for accommodating the pin 42 in different positions of the ring 40. Upon removal of the pin 42, the ring 40 may be turned one half or a multiple of one half turn and thereafter the pin 42 can be reinserted into the slot 43.

The mechanism so far described is typical for arrangements heretofore used. During operation the spindle 20 with the flyweight 21 is normally held in the position shown in the drawing by action of the spring 38 counteracting the centrifugal force on the flyweight. If the speed rises beyond normal operating speed the flyweight 21 is gradually forced outward, that is, downward when viewed in the drawing, against the biasing force of the governor spring 38. At emergency speed, which may be 10% above normal operating speed, the main flyweight engages the trip finger 12 which in turn causes through known mechanisms, not shown, the turbine valves to close.

The mechanism may be tested at lower speeds by supplying liquid from the conduit 31 to the chambers 27, 28 of the main flyweight. During testing the increase in mass of the main flyweight caused by the supply of liquid to the chambers 27, 28 effects tripping or operation of the mechanism at a lower speed. The liquid is discharged from the chambers 27, 28 through the aforementioned openings 29, 30 which as indicated in the drawing are substantially smaller than the supply openings or ports 33.

If such mechanism were designed for a normal operating speed of 5000 R. P. M. or higher the chambers 27, 28 would have to be made of considerable size to permit testing of the mechanism at a low speed of, say 1000 R. P. M.

In accordance with my invention as indicated above, I provide means permitting such governor when used as an emergency governor to be tested at a small fraction of its normal operating speed. This means in the embodiment shown in the drawing includes an auxiliary or second flyweight comprising a ring 44 surrounding the spindle 20 inside the cylindrical support 13 and biased towards a shoulder 45 formed by the aforementioned nut 40 by means of a spring 46 having a lower end engaging the ring 44 and an upper

end engaging the plug 34. The system thus includes flyweights 21 and 44 subject to centrifugal forces with springs 38 and 46 respectively opposing said forces.

The system rotates about an axis which is the centerline of the shaft 10 and the support 13. When viewed in the position shown the main or first flyweight 21 tending to move downward is biased by the spring 38 in upward direction, whereas the auxiliary or second flyweight 44 tending to move upward is biased downward by the spring 46. Thus, the forces of the two flyweights are in opposition and the resultant of the two forces is the differential thereof. This differential is a function of the masses of the flyweights, the radius at which they rotate, the characteristics of the springs opposing them and the speed. At low speed the centrifugal force on the first flyweight is comparatively large and that on the second flyweight is comparatively small. This is due not only to the fact that the second flyweight 44 has a much smaller mass than the first flyweight 21 but primarily due to the fact that the second flyweight 44 has a center of gravity 47 which at low speed is located close to the center of rotation 48 of the system while the first flyweight 21 has a comparatively great mass with a center of gravity 49 at a greater distance or radius from the center of rotation.

The whole system at low speed has a center of gravity 50 which in Fig. 2 is located below the center of rotation and naturally above the center of gravity 49 of the first flyweight in the position shown in the drawing. As the second flyweight at low speed produces a comparatively small force in opposition to the greater centrifugal force of the first flyweight it is possible to cause actuation or tripping of the mechanism at low speed by the supply of a comparatively small amount of liquid to the chambers 27, 28. In other words, it is possible at low speed to overcome the opposing force of the second flyweight and to increase the force of the main flyweight sufficiently to cause the latter to move outward against the biasing force of the spring 38. With increasing speed the second flyweight 44 is moved outward, that is, upward in the drawing, until at a certain speed it reaches the position indicated in dash-dotted lines in Fig. 2. Its center of gravity 47 then has moved upward a considerable distance into the position 51. Let us assume that during this movement of the second flyweight 44 the first flyweight 21 has remained in its original position due to the biasing effect of the comparatively strong spring 38. The center of gravity 50 of the entire system then must have moved upward into a new position 52. With a further increase in speed the centrifugal force exerted on the first flyweight 21 overcomes the force of the spring 38 together with the opposing force of the second flyweight. The main flyweight together with the spindle is moved outward, that is, downward in the drawing, to engage the element 12. Under this condition the center of gravity 49 of the first flyweight is moved outward into the position 53. If the normal operating speed of the turbine to which the governor is attached is 5000 R. P. M., outward movement of the main governor weight and tripping of the finger 12 may take place at a speed of say 5500 R. P. M.

If the turbine has been operating at normal speed of 5000 R. P. M. and the emergency governing mechanism is to be tested at this speed, the valved conduit 31 is opened and oil or like

liquid is supplied to the chambers 27, 28 to cause tripping of the mechanism.

Thus, this mechanism may be tripped at a speed near its normal operating speed by the supply of oil to the chambers 27, 28 and it may also be tripped at a considerably lower speed of the order of one fifth, for instance of its normal operating speed as described above. This has been made possible by the provision of an auxiliary or second flyweight creating a centrifugal force opposing that of the main or first flyweight and increasing with increasing speed at a rate greater than that of the first flyweight. For example, at one fifth of the normal operating speed the centrifugal force exerted on the second flyweight may be equal to one fifth only of the centrifugal force exerted on the first flyweight, whereas at a speed equal to three fifths of the normal operating speed the centrifugal force created by the second flyweight is greater than three fifths of the centrifugal force created by the first flyweight.

The governor may be readily adjusted by changing the position of the nut 40 on the spindle 20. If the nut 40 is turned downward on the spindle the initial compression of the spring 38 is increased and that of the spring 46 is simultaneously decreased, resulting in a higher tripping speed. The action of the governor may be further varied during operation by changing the ratio of mass of the two flyweights. This is accomplished in the present instance by supplying liquid from the valved supply conduit 31 to the chambers or cups 27, 28 of the main flyweight

21. This liquid supply means accordingly broadly constitutes a means for varying the mass of one of the flyweights during operation. At certain high speeds the flyweights are stopped from further outward movement and thereby rendered inoperative by the cylindrical support 13. As the first flyweight is forced outward its upper portion in the drawing, that is, the spacer 34, engages the adjacent wall of the cylindrical support which latter constitutes a stop limiting outward movement of the main flyweight. Similarly, at a certain high speed the second flyweight 44 engages a cylindrical projection or stop 55 forming an extension of the bushing 19 preventing further outward movement of the latter. In place of the rigid projection 55 flexible or yieldable means, such as an additional spring, may be provided which above a certain speed aids the spring 46 in biasing the second flyweight 44 against centrifugal force.

Having described the method of operation of my invention, together with the apparatus which I now consider to represent the best embodiment thereof, I desire to have it understood that the apparatus shown is only illustrative and that the invention may be carried out by other means.

What I claim as new and desire to secure by Letters Patent of the United States is:

1. Centrifugal type speed governing mechanism comprising a support, a first flyweight, means including a spring biasing the first flyweight towards the support, a second flyweight and a biasing spring engaging the second flyweight and arranged to counteract movement of the first flyweight during operation, the flyweights having centers of gravity located on opposite sides and at different radii from the center of rotation of the support, and means connected to the flyweights and movable in response to changes of the differential centrifugal force of the flyweights.

2. Centrifugal type speed governing mechanism comprising a cylindrical support, a spindle slidably projecting through diametrically opposite openings in the support, a main flyweight secured to an end of the spindle outside of the support, a biasing spring surrounding the spindle inside the support to oppose movement of the spindle by action of centrifugal force exerted on the main flyweight, an auxiliary flyweight surrounding the spindle inside the support, and a spring engaging the spindle and the auxiliary flyweight opposing centrifugal force exerted on the auxiliary flyweight, the centers of gravity of the flyweights being located on opposite sides of the axis of rotation and the auxiliary flyweight being arranged to oppose movement of the spindle by action of the main flyweight in order to produce movement of the spindle in response to changes of the differential centrifugal force of the flyweights.

3. Centrifugal type speed governing mechanism comprising a cylindrical support having diametrically opposite openings, a spindle within the support having end portions projecting through the openings, a main flyweight connected to the spindle outside the support, a spring surrounding the spindle inside the support to bias the main flyweight against centrifugal force, an auxiliary flyweight engaging the spindle inside the support to oppose movement of the main flyweight, and a spring surrounding the spindle and engaging the auxiliary flyweight to bias the latter against centrifugal force.

35. 4. Centrifugal type emergency speed governing mechanism comprising a cylindrical support having diametrically opposite openings, a spindle projecting through the openings and forming shoulders inside the support, a main flyweight 40 forming a chamber being secured to an end portion of the spindle outside the support, spring means biasing the main flyweight towards the support and an auxiliary flyweight engaging the shoulder on the spindle inside the support and a spring surrounding the spindle and biasing the auxiliary flyweight against centrifugal force, the center of gravity of the auxiliary flyweight and the center of gravity of the main flyweight being located on opposite sides from the center of rotation and the centrifugal forces of the two flyweights opposing each other and the center of gravity of the auxiliary flyweight being located at low speed considerably closer to the center of rotation than the center of gravity of the main flyweight to permit testing of the governor by the supply of a comparatively small amount of liquid into said chambers at a speed considerably below the normal operating speed.

5. Centrifugal type speed governing mechanism comprising a rotatable support, means including first and second flyweights arranged on opposite sides of the center of the support and movable independently of and in opposition to each other, separate biasing spring means for the flyweights, stop means to limit movement of one of the flyweights at a predetermined speed, one of the flyweights forming a chamber, and means including a liquid supply conduit for conducting liquid to said chamber to vary the mass of said last mentioned flyweight.

6. Centrifugal type speed governing mechanism comprising means including a flyweight and a spring opposing movement of the flyweight, other means including a flyweight independently movable of the first flyweight and opposing move-

ment of the latter, means for varying the mass of one of the flyweights during operation, and means responsive to changes of the differential of centrifugal forces acting on the flyweights.

7. Centrifugal type speed governing mechanism comprising a rotatable support, a spindle rotatable with the support, first spring-biased flyweight means held on the support and connected to the spindle to move the latter upon

speed changes, second spring-biased flyweight means held on the spindle to oppose movement of the latter by action of the first spring-biased flyweight means in order to produce movement of the spindle responsive to the differential centrifugal force of the two spring-biased flyweight means.

HAROLD M. OTTO.
